United States Patent Office

Des. 181,814
Patented Dec. 31, 1957

181,814

LAWN SPRINKLER

Dominick A. Saporito, Royal Oak, Mich., and Robert G. Smith, Bronxville, N. Y., assignors to Atlas Press Company, Kalamazoo, Mich., a corporation of Michigan

Application September 26, 1956, Serial No. 43,093

Term of patent 14 years

(Cl. D91—1)

Figure 1 is a perspective view of a lawn sprinkler embodying our new design.

Figure 2 is a side elevational view of said lawn sprinkler.

Figure 3 is a top plan view of said lawn sprinkler.

Figure 4 is a rear end elevational view of said lawn sprinkler.

Figure 5 is a front end elevational view of said lawn sprinkler.

The characteristic features of the lawn sprinkler reside in the portions shown in solid lines.

We claim:

The ornamental design for a lawn sprinkler, as shown and described.
